(57) **CLAIM**

The ornamental design for a multiple bay kennel, as shown and described.

DESCRIPTION

FIG. 1 is an isometric view of multiple bay kennel showing my new design;

FIG. 2 is a front elevational view of FIG. 1;

FIG. 3 is a rear elevational view of FIG. 1;

FIG. 4 is a right elevational view of FIG. 1;

FIG. 5 is a left side elevational view of FIG. 1;

FIG. 6 is a top plan view of FIG. 1; and,

FIG. 7 is a bottom plan view of FIG. 1.

The broken lines in the drawings depict portions of multiple bay kennel that form no part of the claimed design.

1 Claim, 6 Drawing Sheets
